OIL BURNER

Arthur P. Scott, Westminster, Md.

Application March 2, 1938, Serial No. 193,554

16 Claims. (Cl. 158—91)

This invention relates to improvements in oil burners and more particularly to wickless type oil burners such as are used for general heating of agricultural buildings, poultry houses, tobacco barns, garages, etc.

The invention has for its general objects: to provide a low cost, more efficient burner which will permit less carbonization in the oil supply line; to provide control of primary and secondary air supplied to the burner; to permit adjustment of the vaporizing area; to supply improved means for varying the amount of preheat of the oil so as to provide more efficient burning of a wider range of fuel oils; to furnish air cooling and greater protection for the cleaning tube; to supply improved means whereby sufficient carbon can be cleaned from vital burner parts; to provide reasonable oil flow and vaporization without removing all of the carbon which is beneficial to burner operation; to furnish a burner having a cover which can be removed without disturbing the cleaning tube; to provide a burner with directional wings on the flame spreader so that the latter will help to preheat both the air and oil vapors; to provide unique means for preheating both the primary and secondary air supplies; and also to provide manually or automatically controlled air supply means.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a diametrical vertical sectional view of a stove provided with my improvements and with parts broken away to facilitate illustration.

Fig. 2 is a transverse substantially horizontal sectional view taken on the line 2—2 of Fig. 1.

Fig. 3 is a bottom plane view of the flame spreader.

Fig. 4 is a side elevation of a modified form of preheater or cleaning plate.

Referring to the drawings, 5 designates the casing of a stove which may be of any suitable shape and supported by any suitable means. Within the casing is a combustion chamber 6 and a secondary air preheating chamber 7. The latter is formed between the bottom 8 of the casing and a false bottom 9.

A main burner member 9a is arranged in the central portion of the casing and it is preferably

formed of a metal casting to provide a central bowl 10 which receives the oil through a pipe 11 provided with a control valve 12.

The upper end of the bowl forms an annular wall 13 having notches 14 in its upper end arranged between spaced upstanding posts 15.

An oscillatable combined preheating and scraping plate 16 is provided with radially extending lugs 17 which extend through the notches 14 and rest on the horizontal surfaces 18 formed by the bottoms of the notches. As the plate 16 is of less diameter than the internal diameter of the upper end of the bowl, it will be understood that oil from the bowl can overflow through the notches. Furthermore, as the lugs 17 are of less width than the notches, it will be understood that if the plate 16 is oscillated in a manner herein-after described, the lugs will act to scrape or clean the surfaces 18.

The upper end of the plate 16 may be bifurcated and the fork may be spanned by a pin 19 to permit a tool to be inserted for use in removing the plate 16.

A flame spreader 20 cooperates with the parts previously described and such spreader may consist of an annular casting forming a disc 21 having a depending annular skirt 22. Externally of the skirt, the flame spreader is provided with a number of spaced outside legs 23, preferably four in number, and the lower edges of these legs are rabbeted at 24 and the rabbeted portions rest on the upper edge of the outer wall 25 of an annular trough 26 that surrounds the bowl 10. The edge of said wall is preferably arranged below the surfaces 18. At this point it will be noted that if the flame spreader is oscillated about its vertical axis, the rabbeted portions 24 will function to scrape spaced portions of the upper edge of the wall 25 but will allow carbon to remain on portions of such edge between said spaced portions. It will also be observed that if the flame spreader is oscillated, its legs 23 will contact with the lugs 17 of the plate 16 to cause oscillation of the latter.

Each leg 23 has an arc shaped portion 27 (Figs. 2 and 3) and these portions embrace the exterior of the bowl 10 and function to regulate the amount of primary air used and amount of primary vaporization and preheating of the oil as will be explained later.

The flame spreader is also provided with shorter internal legs 28 which are positioned slightly above the upper ends of posts 15 and serve to scrape the upper ends of these parts when the flame spreader is oscillated.

A combined primary air preheating tube and flame spreader operating member 29 has its lower end secured to the flame spreader as shown at 30. The upper end of the tube surrounds the 5 depending annular flange of a removable cover 31, and the flange is detachably connected to the tube by means of a notch and rod connection 32. Consequently the tube and flame spreader can be turned by use of the handles 33 of the cover and 10 when desired the cover can be removed without disturbing the tube or flame spreader.

The main casting 5a forms an outside annular trough 34 which is considerably larger than the trough 26 and surrounds the latter, and the outer wall 35 of the trough 34 is provided with 15 openings or ports 36 to allow secondary air to flow from the preheating chamber 7 into the trough 34.

An annular cover plate 31 closes the major 20 portion of the upper end of the trough 34 but provides an annular throat 38 (Fig. 2) for the passage of the flame.

The introduction of the secondary air to the chamber 7 is permitted by ports 38a and also 25 by ports 39 and 40 in the bottom of the casing. Ports 39 and 40 are controlled respectively by any suitable means, such as rotatable dampers 41 and 42. The damper 42 may be manually controlled, and the damper 41 may be controlled 30 by means of a suitable thermostat 43 arranged exteriorly of the casing of the stove.

The secondary air entering through the ports 38a is directed upwardly by a baffle 38b arranged 35 in the chamber 7 so that it is caused to sweep along the hot bottom 8 of the casing before entering the trough 34.

In operation it will be understood that primary air is supplied through the preheating tube 29 and secondary air through the ports 38a, 39 and 40. The oil enters through the bowl 10 which forms a preheat zone due to the presence of the plate 16 and it will be noted that the bottom surface of the latter is provided with an insulating cavity 44 so that the center portion of the 45 plate is raised above the oil level. With this design, the highly preheated air entering through tube 29 will be deflected into the combustion area and will preheat the oil only a small degree and consequently carbonization will be materially reduced in the oil intake lines. When 50 heavier grades of fuel oil are burned, the plate 16 is preferably provided with a depending cone 45 as shown in Fig. 4, and this cone will extend into the bowl 10 so that a considerable amount 55 of heated metal is submerged in the oil to cause a considerable transfer of heat from the primary air into the oil below the preheater.

The oil flows from the bowl over the surfaces 18 and downwardly between the legs 23 of the 60 flame spreader into the circular oil ring or trough 26 where further quantities are vaporized. As before stated, the amount of preheated primary air meeting oil above the trough 26 may be regulated by turning the tube 29. By 65 such means, lower adjustments of oil flow which means a lower stove temperature, will provide additional vaporization with less air, while in reversing the operation with a higher oil flow and higher oil temperatures it is better to provide less vaporizing area and increased primary air supply.

The secondary air enters through the ports 38a, 39 and 40 and is directed against the hot bottom 8 of the stove before it enters the trough 70 or outer oil vaporizing ring 34. This air will

provide sufficient oxygen to support combustion which takes place in the area adjacent to the flame spreader legs 23 and is directed outwardly by the general curved contour 46 of the under-surface of the disc 21. This tends to provide a 5 flame of greater diameter and to hold the flame in the lower portion of the stove drum for greater efficiency.

Many burners in the general practice receive 10 air through perforations in the circumference of the burner, and because of mechanical construction, necessary uniform air conditions can not be provided over the entire area. One great advantage of my burner is that through the use 15 of these inlets can be staggered to provide for more uniform air conditions and much more readily eliminate inefficiency which results in carbonization, smoke, and unburned vapors.

Due to the presence of the damper 42, the 20 openings 40 can be regulated manually whenever the operator changes the temperature adjustment on the oil supply valve 12 which will greatly increase or decrease the oil supply and the corresponding amount of air required. Means 39, 41 are also provided to automatically 25 control the introduction of air so that when the temperature of the stove and corresponding air decreases, showing lower oil consumption, the air inlets 39 will automatically close and when the temperature of the stove and surrounding 30 air becomes hotter, showing greater oil consumption, the auxiliary air holes 39 will be opened to allow additional air and thereby increase the efficiency of combustion.

In reference to cleaning, it will be observed 35 that the plate 16 is to clean a portion of the carbon which may collect in the notches through which the oil flows and to help remove carbon which might restrict the area between the legs 23 and the burner. A special feature of my design 40 is that this cleaner can only be oscillated and remove a portion of the carbon. It cannot be rotated a complete revolution to remove all of the carbon forming on these edges.

A further improvement over existing designs 45 is that I provide more efficient air-cooled protection for the means 29 which actuates the flame spreader or vaporizer cleaner. Heretofore, to the best of my knowledge, rods have generally been used for this purpose and they 50 are subject to direct interior temperatures of the stoves, and it has been necessary to provide additional metal protection for such rods. By using the air preheating tube, I provide this 55 protection in a more efficient and less expensive way, as the cooling air is also used to support combustion in the burner.

Furthermore, in the prior constructions, the 60 cleaning rod and cover must be removed at the same time, whereas in my construction, the units 29 and 31 are detachably connected together so that the cover can be removed and the condition of the interior of the stove may be more carefully observed without disturbing 65 the cleaner or other parts of the burner.

The herein described and illustrated embodiments of my invention have given satisfactory results, and it will be obvious to those skilled in the art that other changes and modifications 70 may be made without departing from the spirit and scope of the invention, and it is intended that all matters contained in the above description or shown in the drawings shall be interpreted as illustrative and not in a limiting sense. 75

What I claim and desire to secure by Letters Patent is:

1. In a burner of the character described, a main burner member having a central bowl provided with a notched upper end, means for supplying oil to the bowl, a preheating plate having outwardly extending lugs of less width than the notches, extending through the latter and resting on the bottoms of the notches, a trough 10 surrounding the bowl and adapted to receive oil overflowing from the bowl through said notches, and means for turning said plate and for scraping limited portions of the upper edge of the outer wall of said trough, said lugs cooperating 15 with the notches of the bowl to prevent the last-mentioned means from scraping more than limited portions of the upper edge of the outer wall of the trough.

2. In a burner of the character described, a main burner member having a central bowl provided with a notched upper end, means for supplying oil to the bowl, a preheating plate having outwardly extending lugs of less width than the notches, extending through the latter and resting on the bottoms of the notches, a trough 20 surrounding the bowl and adapted to receive oil overflowing from the bowl through said notches, means for turning said plate and for scraping portions of the upper edge of the outer wall of said trough, said lugs being prevented by the notches from turning with the plate more than a predetermined degree and cooperating with the last-mentioned means to prevent said means from scraping more than limited portions of the upper edge of the outer wall of the trough, a heating 25 chamber arranged externally of the trough and communicating with the latter, and means for supplying air to said chamber.

3. In a burner of the character described, a main burner member having a central bowl provided with a notched upper end, means for supplying oil to the bowl, a preheating plate having outwardly extending lugs of less width than the notches, extending through the latter and resting on the bottom of the notches, inner and outer troughs surrounding the bowl, the inner trough being arranged to receive oil overflowing from the bowl through said notches, means for rotating said plate and for scraping limited portions of the upper edges of the outer wall of said trough, an annular cover for the outer trough forming a throat above the inner trough, and means for supplying air to the outer trough.

4. In a burner of the character described, a main burner member having a central bowl provided with a notched upper end, means for supplying oil to the bowl, a preheating plate having outwardly extending lugs of less width than the notches, extending through the latter and resting on the bottom of the notches, means for rotating said plate, the last-mentioned means comprising a flame spreader having legs engageable with said lugs.

5. In a burner of the character described, a main burner member having a central bowl provided with a notched upper end, means for supplying oil to the bowl, a preheating plate having outwardly extending lugs of less width than the notches, extending through the latter and resting on the bottom of the notches, means for rotating said plate, the last-mentioned means comprising an annular flame spreader forming a primary air inlet and provided with spaced legs adapted to contact with said lugs in order to turn the plate when the flame spreader is oscillated.

6. In a burner of the character described, a main burner member having a central bowl provided with a notched upper end, means for supplying oil to the bowl, a preheating plate having outwardly extending lugs of less width than the notches, extending through the latter and resting on the bottom of the notches, means for rotating said plate, the last-mentioned means comprising an annular flame spreader provided with external legs having arc-shaped wings slidably engaging the outer surface of the bowl.

7. In a burner of the character described, a main burner member having a central bowl provided with a notched upper end, means for supplying oil to the bowl, a preheating plate having outwardly extending lugs of less width than the notches, extending through the latter and resting on the bottom of the notches, means for rotating said plate, the last-mentioned means comprising an annular flame spreader provided with internal legs arranged above the upper edge of the bowl and adapted to scrape the upper edges of said lugs.

8. In a burner of the character described, a main burner member having a central bowl provided with a notched upper end, means for supplying oil to the bowl, a preheating plate having outwardly extending lugs of less width than the notches, extending through the latter and resting on the bottom of the notches, means for rotating said plate, the last-mentioned means comprising a flame spreader formed of a disc having legs engageable with said lugs and having an upwardly and outwardly curved undersurface arranged above the lugs.

9. In a burner of the character described, a main burner member having a central bowl provided with a notched upper end, means for supplying oil to the bowl, a preheating plate having outwardly extending lugs of less width than the notches, extending through the latter and resting on the bottom of the notches, means for rotating said plate, the last-mentioned means comprising an annular flame spreader forming a primary air inlet and provided with internal and external legs, the internal legs being arranged above the upper edges of the bowl, and the external legs being arranged to abut against said lugs when the flame spreader is turned.

10. In a burner of the character described, a main burner member, an oscillatable plate slidably resting on the main burner member, means for supplying oil to the main burner member at a point below said plate, a turnable flame spreader cooperating with the plate and adapted to turn the latter, an air preheating tube projecting from the flame spreader, and a cover detachably connected to the tube and adapted to turn the tube and flame spreader when the cover is turned.

11. In a burner of the character described, a main burner member, an oscillatable plate slidably resting on the main burner member, means for supplying oil to the main burner member at a point below said plate, a turnable flame spreader cooperating with the plate and adapted to turn the latter, an air preheating tube projecting from the flame spreader, and a cover detachably connected to the tube and adapted to turn the tube and flame spreader when the cover is turned, said plate having a depending portion extending downwardly into said bowl.

12. A burner of the character described, comprising a main burner member forming a central bowl and inner and outer troughs which

surround the bowl, means for supplying oil to the bowl, the wall of the bowl being provided with spaced notches to allow oil to overflow the bowl into the inner trough, a turnable plate of 5 less diameter than the internal diameter of the upper end of the bowl and having outwardly extending lugs of less width than the notches, 10 slidably resting on the bottom of the notches, an annular flame spreader having legs slidably resting on the outer wall of the inner trough, a primary air preheating tube projecting upwardly from the flame spreader and secured to the latter, a cover plate for the outer trough forming an annular throat surrounding portions 15 of the flame spreader, and means for supplying secondary air to the outer trough.

13. A burner of the character described, comprising a main burner member forming a central bowl and inner and outer troughs which surround 20 the bowl, means for supplying oil to the bowl, the wall of the bowl being provided with spaced notches to allow oil to overflow the bowl into the inner trough, a turnable plate, of less diameter than the internal diameter of the upper 25 end of the bowl and having outwardly extending lugs of less width than the notches, slidably resting on the bottom of the notches, an annular flame spreader having legs slidably resting on the outer wall of the inner trough, a primary air preheating tube projecting upwardly 30 from the flame spreader and secured to the latter, a cover plate for the outer trough forming an annular throat surrounding portions of the flame spreader, means for supplying secondary air to the outer trough, and an annular cover plate detachably secured to the upper 35 end portion of the primary air preheating tube.

14. A burner of the character described, comprising a main burner member forming a central bowl and inner and outer troughs which surround the bowl, means for supplying oil to the bowl, the wall of the bowl being provided with spaced notches to allow oil to overflow the bowl 40

into the inner trough, a turnable plate of less diameter than the internal diameter of the upper end of the bowl and having outwardly extending lugs of less width than the notches, 5 slidably resting on the bottom of the notches, an annular flame spreader having legs slidably resting on the upper edges of the bowl and outer wall of the inner trough, a primary air preheating tube projecting upwardly from the flame spreader and secured to the latter, an annular cover plate for the outer trough forming an annular throat surrounding portions of the flame spreader, means for supplying secondary air to the outer trough, and arc-shaped wings forming part of the flame spreader and 10 slidably engaging the exterior of the wall of the bowl.

15. In a burner of the character described, a main burner member having a central bowl provided with a notched upper end, an oil ring 20 surrounding the bowl and having an outer wall, an annular flame spreader arranged above the bowl and ring and having legs slidably resting on said wall, wings secured to the legs and cooperating with the notches to regulate the amount 25 of primary air flowing through the flame spreader toward the oil ring, and means for supplying primary air to the flame spreader and for turning the latter.

16. In a burner of the character described, a main burner member having a center bowl provided with a notched upper end, means for supplying oil to the bowl, a trough surrounding the bowl and having an outer wall, a preheating plate having outwardly extending lugs of less 35 width than the notches, extending through the latter and resting on the bottoms of the notches, and means for turning the plate and for scraping limited portions of the upper edge of said outer wall of the trough, said notches and lugs 40 functioning to limit the turning movement of said means.

ARTHUR P. SCOTT.
